UNITED STATES PATENT OFFICE.

JAMES JOSEPH GRIFFIN, OF SAN FRANCISCO, CALIFORNIA, AND GORDON MOFFITT PEACOCK, OF SOUTH YARRA, MELBOURNE, VICTORIA, AUSTRALIA.

DOUBLE-SEAMING MACHINE.

1,091,836.

Specification of Letters Patent. Patented Mar. 31, 1914.

Application filed March 15, 1911. Serial No. 614,698.

To all whom it may concern:

Be it known that we, JAMES JOSEPH GRIFFIN, a citizen of the United States of America, and a resident of the city of San Francisco, in the State of California, United States of America, (whose post-office address is at 1131 Shotwell street, in the said city of San Francisco, but who is temporarily residing at 1 Garden street, South Yarra, a suburb of the city of Melbourne, in the county of Bourke, State of Victoria, Commonwealth of Australia,) and GORDON MORRIS PEACOCK, a subject of the King of Great Britain and Ireland, and a resident of 1 Garden street, South Yarra, aforesaid, have invented certain new and useful Improvements in Double-Seaming Machines, of which the following is a specification.

This invention relates to tins, canisters, or vessels, hereinafter termed cans, often used for containing alimentary substances and generally consisting of cylindrical bodies each having a vertical seam therein and a circumferential flange at the top and bottom thereof. Both ends of the can are usually closed by a disk also provided with a circumferential flange, the relative flange of the body and the flange of the disk being double seamed together.

In prior application for United States patent filed on the 13th day of January, 1911, Serial No. 602,409, by the present applicants it has been suggested to partially crimp an end or closing disk to a can body in order to firmly hold the end in position ready for double seaming and it is now proposed to use cans so treated with the machine about to be disclosed although such machine is not restricted to use with such cans.

The foremost of the present objects in view are to provide a double seaming machine capable of treating a multiplicity of cans simultaneously, each seaming mechanism being independently controlled, readily accommodating cans varying slightly in height, and, by flattening, re-forming, or correctly shaping the flanges prior to seaming, and accommodating the extra thickness of metal of the body vertical seam during double seaming, producing a perfect seam and not damaging any cans. In addition a common feed possessing simplicity is used for all the seaming mechanisms and permits

of mixed cans being fed *i. e.* some full and some empty.

Other objects and advantages will be in part obvious and in part pointed out hereinafter.

Referring to the drawings which form part of this specification and are to be read herewith and from some of the various figures of which details and parts have occasionally been omitted or broken away for convenience of illustration, Figure 1 is a front view of the machine embodied in our invention. Fig. 2 is a plan of a can treated according to the invention embodied in prior United States application, Serial No. 602,409 aforementioned. Fig. 3 is a section on line Z, Fig. 2. Fig. 4 is a section on line Y Fig. 2. Fig. 5 is a section through a can body showing the double thickness of metal of the vertical seam thereof. Fig. 6 is a plan of the machine embodied in our invention. Fig. 7 is a plan of the feeding means. Fig. 8 is a longitudinal section of parts shown in Fig. 7 on line X. Fig. 9 is a cross section of parts shown in Fig. 7 on line W. Fig. 10 is a detail view showing a large cam used in the machine. Fig. 11 is a detail view of a small cam used in the machine and a lifting rod actuated thereby. Fig. 12 is an end elevation of the machine embodied in our invention. Fig. 13 is a sectional detail view of a large and small cam used in the machine. Fig. 14 is a sectional view of a segmental head. Fig. 14^A is a plan of a segmental head. Fig. 15 is a sectional view of a modified form of segmental head. Fig. 16 is a detail view of a slide and its actuating means. Fig. 17 is a cross section of the slide. Fig. 18 is a detail view of a chuck and a flange reformer. Fig. 18^A is a detail view of a chuck and a modified flange reformer. Fig. 19 is a detail view of a slide control. Fig. 20 is a detail view of means for accommodating cans varying in height. Fig. 21 is a cross section of the parts shown in Fig. 19. Fig. 22 is a detail view of an ordinary can before being operated upon by the flange reformer. Fig. 23 is a detail view of means for accommodating the extra thickness of metal entailed by the vertical seam of a can body. Fig. 24 is a detail view of a can after being operated upon by a flange reformer and before double seaming. Fig. 25 shows a defect commonly

occurring during double seaming and which the flange reformer prevents. Fig. 26 is a detail view of a seaming head and relative parts. Fig. 27 is a detail view to show the action of the first of a pair of seaming rollers. Fig. 28 is a detail view of a deformed closing disk or end which the flange reformer flattens or correctly shapes. Fig. 29 is a detail view showing the effect of the seaming rollers upon a closing disk, such as seen in Fig. 28, without the flange reformers. Fig. 30 is a detail view to show the action of the second of a pair of seaming rollers.

15 The can herein chosen for illustrative purposes, it will be seen, comprises a can body 202 having a vertical seam or lap joint 203 and an outstanding circumferential flange 204 around its top and bottom. Each end is closed by a disk 205 provided with a central depression 206 and a circumferential flange 207. Preferably such cans before being fed to the machine about to be described have the flange 207 partially crimped or turned beneath the flange 204 at opposite sides thereof as shown at 208.

The invention includes a framework 7, provided near its front with inner side pieces 8 having between them openings 9 and outer side pieces 10 having between them openings 11. At each side of each opening 9 and projecting thereto may be a plate spring 9^a. Between the inner and outer side pieces 8 and 10 passes a wide feed belt 12. Adjacent to the outer side pieces is an outermost side piece 13. Between the outer side pieces 10 and the outermost side piece 13, passes a return belt 13^a. The outermost side piece 13 may be provided with a 40 return guide portion 13^b having beneath it a slot or passageway to accommodate the belt 13^a. Adjoining the portion 13^b may be a return opening 11^a. Attached to each inner side piece 8 above the feed belt 12 is an inner deflecting guide 14. In each inner guide 14 is a slide space 15. Attached to each outer side piece 10, above the feed belt 12 is an outer deflecting guide 16. At one end of the framework is a combined inner and outer 50 end deflecting guide. This is attached to the one end of the inner side pieces 8 and the end one of the outer side pieces 10, extending therebetween, and consists of an inner deflecting portion 17 and an outer deflecting portion 18. Adjacent to each of the openings 9 and formed in the framework is a passage 19 for the segmental head 53, having above it a can rest or cross 20.

At the feed end of the framework is a 60 pulley 21 secured to a shaft 22 at the inner end of which is a pinion 23 engaging with a spur wheel 24, upon a counter shaft 25. Secured to the countershaft 25 is a pinion 26 engaging with a spur wheel 27 upon a longitudinal main shaft 28, suitably bearing

in the framework. Attached to the longitudinal shaft 28 at the delivery end of the framework is a bevel wheel 29 engaging with a bevel wheel 30 upon a cross shaft 31. Attached to the cross shaft 31 is also a bevel wheel 32.

Secured to the longitudinal main shaft 28 are a series of large cams 33 each of which is provided with a sinuous groove 34. Engaging in each groove 34 is a roller 35, mounted at one end of a lower intermediately pivoted lever 36 pivoted by a pivot pin 37 to the framework. Pivoted to the other end of each lower intermediately pivoted lever 36 is a vertical connecting rod 38 having 80 interposed in its length a coupling or turnbuckle 39. Pivoted to the upper end of each vertical connecting rod 38 is an upper intermediately pivoted lever 40 pivoted by a pivot pin 41 to the framework and having at 85 its inner end a fork 42.

Attached to each of the large cams 33 is a small cam 43. Engaging with the periphery of each cam 43 is a roller 44 carried by a lever 45 pivoted by a pivot pin 46 to the framework. Each cam 43 and the large cam 33 attached thereto is controlled by a clutch 47 of any suitable character which may be operated by lever 47^a.

Resting upon each of the levers 45 is a 95 lifting rod 48 having a lower threaded end 49 threaded into a male member 50 which latter engages with a female member 51 in which reposes a rubber or like cushion 52. Secured to the upper end of each lifting rod 100 is a segmental head 53 provided with four segments 54, between which are spaces 55. Each segment is provided with an inclined inner and upper face 56.

In each of two opposite segments 54 may be formed a vertical slotway 54^a across the bottom of which is a pivot pin 54^b. Pivoted to each pivot pin 54^b in each slotway is a can holder 54^c provided with a protuberance 54^d. Each holder is provided with an 110 inclined inner and upper face 56^a, and below each face with an inner milled gripping edge 54^e. Between each segment 54 and its holder 54^c is a spring 54^f. Protruding from the table or an extension thereof are set 115 screws 7^a for engagement with the can holders.

Engaging with the bevel wheel 52 (Fig. 12) is a bevel wheel 57 secured at the bottom of a vertical shaft 58 intermediately situated upon which is a box cam 59 provided with a sinuous groove 60. Engaging with the groove 60 is a roller 61 carried by the short arm 62 of a bell crank lever which latter is pivoted by a pivot pin 63 to the framework. To the long arm 64 of the bell crank lever is pivoted one end of a link 65 to the other end of which is pivoted a lever 66, attached to a rocking shaft 67. Loosely surrounding said rocking shaft 67 are a series 130

- of levers 68 each provided in its boss with a round hole 69. Upon the said rocking shaft are a series of collars 70 each of which adjoins one of the levers 68. Each collar is loose upon the said shaft. In the rocking shaft beneath each collar is a key recess 71 across one end of which is a pivot pin 72 (Figs. 19 and 21) and seated at the other end of which is a spiral or like spring 73.
- 16 Pivoted by the pivot pin 72 is a depressible key 74. Through each collar is a hole 75 in which is a headed pin 76 behind which is a spring 77, the tension of which is adjusted by a screw 78, threaded in the said hole 75 (Fig. 16).
- 17 At the top of the vertical shaft 58 is secured a cam 79 provided with a sinuous groove 80. Engaging in the said groove is a roller 81 mounted at the end of a lever 82, which lever is secured to a shaft 83 mounted longitudinally along the top of the framework. Secured to the shaft 83 are a series of levers 84 each having a forked inner end 85.
- 18 At one end of the framework is a pulley 86 driving a rear longitudinal shaft 87. Upon the shaft 87 are a series of bevel wheels 88 each provided with a clutch 89 of any suitable character. Engaging with each bevel wheel 88 is a bevel wheel 90 secured to the outer end of a shaft 91 attached to the inner end of which is a bevel wheel 92. Engaging with each of the bevel wheels 92 is a bevel wheel 93 secured intermediately upon a hollow vertical spindle 94.
- 19 Attached to the bottom of each spindle 94 is a seaming head 95 upstanding above which are two pairs of opposite lugs 96 each pair carrying a pivot pin 97. Mounted on each of the pivot pins 97 is an intermediate pivoted lever 98 in the bottom of which is an in cut or recess 99. In the said seaming head 95 are two opposite slideways 100 in each of which is a major slide 101. Each major slide carries a cross pin 102 accommodated by the in cut 99 of the lever 98 aforesaid. In each major slide 101 is a minor slide 103, controlled by an adjusting screw 104 and carrying a seaming roller 105.
- 20 Firmly mounted at the top of the lever 98 first actuated, as hereinafter explained, is a roller 108. In the top of the lever 98 last actuated, as hereinafter explained, is a slideway 106 in which is a slide 107 carrying a roller 108. Behind the slide 107 in the slideway 106 is an elastic cushion 109 the tension of which is adjusted by an adjusting slide 110 and a screw 111 (Fig. 23).
- 21 Sliding upon each hollow spindle 94 is a sleeve 112 each provided at the top with a circumferential groove or recess 113. At one side of said sleeve is an inwardly inclined surface 114 opposite which, at the other side of said sleeve, is an outwardly inclined surface 115.
- 22 Within each hollow spindle 94 is a hollow guide and chuck carrier 116 having attached to its bottom a chuck 117. Centrally disposed in the lower surface of the chuck 117 is a recess 118. Around the said lower surface is a circumferential milled flange 119. Within the hollow guide and chuck carrier 116 is a disengaging rod 120 having at its bottom a disk 121 and at its top a recessed or grooved collar 122.
- 23 Attached to each seaming disk, preferably circumferentially between the slides 101, are two devices for flattening, reforming, or correctly shaping the flanges to be double seamed. These are hereinafter called flange reformers 123 and each is provided with a foot 124 bearing upon the upper face of the circumferential flange 119 of the chuck 117 (Fig. 18A). Or reforming rollers 124A may be used to operate in the same manner as the feet 124.
- 24 Attached by a connecting rod 125 and pivot pin 126 to each of the levers 68 is a slide. This consists of two side members 127 united by a bridge piece 128 (Fig. 17). Upstanding above each side member are a series of pivot pins 129 upon each of which moves an arm 130. The arms of each member 127 correspond in situation forming working pairs. Each arm is controlled by a spring 131 one end of which is attached to the said arm the spring then passing around the pivot pin 129 and being attached at its other end to the side member 127. The springs 131A of the second pair of arms are stronger than their fellows. Upstanding above each side member are also a series of stops 132 one for each arm 130. Outstanding from each arm is a limiting protuberance 133 each of which engages with one of the said stops 132.
- 25 The cycle of operations in this machine is as follows: The cans with the ends poised thereon or partially crimped thereto are placed upon the feed belt 12 and traveling therewith come into contact either with inner deflecting guides 14 or outer deflecting guides 16 dependent upon the position occupied upon the belt whether adjacent to the inner side pieces 8 or outer side pieces 10. If coming into contact with an inner deflecting guide 14 it is plain from the conformation of the guide that the can will be retained thereby and that any can which may be immediately following on will pass that guide and be retained by the next. Should a can come into contact with an outer deflecting guide 16 the conformation of the same is such, as shown, as to deflect the can toward the inner guides. Should all the inner guides 14 be retaining cans simultaneously the cans then being fed by the belt 12 will simply pass by each inner deflecting guide 14 successively being projected back between the guides by the outer deflecting guides 16. When the combined inner and outer deflecting guides 14 and 16 have passed the can will be retained by the outer deflecting guides 16.

outer end deflecting guide is reached the cans which cannot be accommodated by the inner guides 14 are simply deflected on to the return belt 13^A and coming into contact with the guide portion 13^B pass through the opening 11^A and are re-fed. Should a block or interruption of cans momentarily occur at any of the inner deflecting guides 14 it is plain that the succeeding cans being fed will simply pass through the openings 11 between the outer side pieces 10 and be returned by the return belt 13^A. Thus the cans can never receive injury and the feed is continuous and need not be stopped. Each can when retained by an inner deflecting guide 14 is prevented from passing freely through its opening 9 by the plate springs 9^A. The can is then half on and half off the feed belt 12. Each can is fully carried through the opening 9 and poised upon its can rest or cross 20 by its relative slide, the end arms 130 each time the slide recedes, carrying a can as far as its cross 20. This will be hereinafter more fully explained. Each segmental head 53, by the rotation of the shaft 28, small cams 43, and lifting of the lifting rods 48 by the levers 45, now has its four segments 54 passed through the passageway 19, the spaces 55 between the segments 54 accommodating the cross 20. Each can is thus lifted by its respective head 53 from the cross 20 and centrally poised upon said head by the inclined inner upper faces 56 thereof. When the can is elevated its end or disk 205 comes into contact with the chuck 117 the milled circumferential flange 119 of which is then seated comfortably within the depression 206 of said disk. The flange of the chuck being milled prevents the can turning. Should the can holders 54^C be employed it is clear that as the head 53 is elevated the protuberances 54^D come into contact with the set screws 7^A. The milled gripping edges 54^E are thus pressed firmly into contact with the can and effectually prevent it turning even in very exceptional circumstances. The foot 124 of each flange reformer 123, or the reforming rollers 124^A, now pass rapidly over the top of the flange 207 of the disk 205 and positively flatten the same and the flange 204 of the can body to right angles with the said body. It does not need explaining that each of the seaming heads 95 carrying the reformers 123 receives its rotary movement from the pulley 86, shaft 87, bevel wheels and hollow vertical spindle 94 and that the chuck 117 does not rotate with the seaming head 95 and hollow spindle 94.

It may be necessary to point out, though, that it sometimes happens that although all cans are thought to be of a uniform height this is not so and slight variations occur.

To overcome this difficulty the cushions 52

are inserted in the female members 51 and it is apparent that upon the male members 50 being depressed on said cushions by the lifting rods 48 the difference in height is absorbed by the cushion 52 and vice versa.

At the same time that the small cams 43 are causing the elevation of the heads 53 the relatively large cam 33 by its sinuous groove 34, roller 35, lower intermediately pivoted lever 36, connecting rod and upper intermediately pivoted lever 40, the forked end 42 of which engages with the groove or recess 113, is causing the sliding sleeve 112 to move upon the hollow vertical spindle. As the sleeve 112 descends the inwardly inclined surface 114 comes into contact with the adjacent roller 108 and by the intermediately pivoted lever 98 moves the corresponding major slide 101 carrying its seaming roller 105 inwardly and into engagement with the can. As the sleeve 112 ascends the outwardly inclined surface 115 comes into contact with its adjacent roller 108 and by the intermediately pivoted lever 98 moves the corresponding major slide 101 carrying its seaming roller 105 inwardly into engagement with the can also. The can end is seamed to the can body by the rollers 105 as is usual. Adjustment of the rollers 105 is effected by the adjusting screws 104 controlling the minor slides 103 to which the rollers are attached. Should there be a defect in the flanges of the can body or the can end, the elastic cushion 109 provides for seaming being properly effected as the final pressure by its influence although firm is gentle and prevents the double seam splitting. This particularly applies to the double thickness of metal in the can body owing to the vertical seam 203.

When double seaming has been effected and the heads 53 by the conformation of the small cams 43 commence to recede, the disk 121 upon the lower end of the disengaging rod 120 presses upon the end of the can and positively and effectually disengages it from the seaming head 95. At the end of the seaming operation the seaming rollers 105 will be disengaged from the can by centrifugal action; although springs might be employed to positively retract the seaming rollers if desired; but said rollers will be moved outward and retained in their outermost position by centrifugal force and until forcibly moved inward by the action of the surfaces or cams 114, 115. The disengaging movement is effected by depression of the rod 120 caused by the actuation of each respective lever 84 which is in turn effected from the shaft 83 in turn actuated by the lever 82 the roller 81 of which operates the said lever by following the sinuosity of the cam 79. The cam 79, it is plain, is rotated by the vertical shaft 58 which is driven by bevel wheels from the longitudinal shaft 28.

As the heads 53 recede the cans with their ends double seamed thereto are once more deposited each upon its can rest or cross 20. The slides now remove the cans. This is effected by the roller 61 following the sinuous groove of the box cam 59 and actuating the bell crank lever which by the link 65 and lever 66 operates the rocking shaft 67 and levers 68. Each lever 68 is by its respective connecting rod 125 and pivot pin 126 engaged with its relative slide. As each slide is moved, for example, toward the openings 9 its two side members 127 pass each side of the can then upon the cross 20 the arms 130 moving freely outwardly to pass the can but assuring their inward positions when past it on account of the springs 131. The inward movement is limited by the stops 132 and protuberances 133. 15 As the slide recedes by the action of the mechanism abovementioned it is clear that the arms 130 bearing up behind the can remove it from the cross 20. The slides may deliver the cans to a chute conveyer or any 20 other device for removing them from the machine.

The first pair of arms of the slide, when a can is being removed from a cross 20, have already engaged the can within the corresponding inner deflecting guide 14 and at the same time that the can is being removed from its cross the said first pair of arms are carrying their can toward the said cross 20. When the cross is reached the slide again 35 moves toward the opening 9 the first pair of arms 130 engaging a new can and another pair of arms 130 bearing behind the can on the cross. The can on the cross is now elevated by the relative segmental head 53 and 40 during such elevation and until the can is again deposited on the cross the slide, by the sinuosity of the groove 60 of the cam 59, remains stationary. It is thus plain that during double seaming a pair of arms 130 45 are bearing against the can being seamed.

As soon as the seamed can is deposited on its cross the slide removes it and places another can in position as already explained. The second pair of arms 130 having the 50 stronger springs 131 prevent the possibility of a can being inadvertently moved toward its cross by any unforeseen circumstance such as the accidental pressure of cans being fed.

Should any obstruction occur to the slide such as an inadvertent accumulation of cans the said slide upon reaching the same and encountering unnatural opposed pressure is automatically thrown out of gear as long 60 as the obstruction exists thereby preventing a can or cans being injured. It automatically re-commences its operations however when the obstruction is removed. This is effected by the pin 76 the point or nose of 65 which is held within the pin hole 69 of the

lever 68 by the respective spring 77 the tension of which, adjustable by the screw 78, is overcome when an obstruction is met permitting the pin 76 to recede from the hole 69 thereby disengaging the lever 68 from the collar 70 which actuates it. 70

Each collar 70 is actuated by the rocking shaft through the agency of the pivoted key 74. By having the key 74 pivoted and spring controlled as shown, by depressing the key 74 and moving any one collar 70 along the shaft out of engagement with its corresponding lever 68 any individual slide may be cut out without interfering with the action of the remainder. The necessity of this is obvious as also is the use of the clutches 89 for disengaging the seaming heads individually and the clutches 47 for disengaging the elevating heads 53 individually. 80

The feeding means has been made the subject of an application filed by us August 24th 1911, Serial No. 645,872.

Having now described our invention, what we claim as new and desire to secure by Letters Patent is:—

1. In a can seaming machine, a rotatable disk, seaming means attached thereto, and flange re-formers attached to said disk, each re-former being provided with a foot. 95

2. In a double seaming machine, the combination of a rotary support, seaming rollers thereon, means for presenting a can to said rollers; means for controlling such presenting means, means for centering the can, means for holding the can stationary, means on said support for re-forming or correctly shaping previously formed flanges prior to seaming them, means for engaging the seaming rollers with the cans to be seamed, means for controlling the said engaging means, means for accommodating circumferential irregularities of any can, and means for discharging the seamed can. 100

3. In a double seaming machine, a lifting rod, a hollow cylindrical head carried thereby and divided by intersecting vertical slots into a plurality of radial segments, each segment having an inwardly inclined face at its upper end, a pivoted can holder adjacent each segment and means for causing said can holders to engage the can when the head is raised, substantially as described. 110

4. In a double seaming machine, a framework, a passage in said framework, a cross above such passage, a lifting rod, a head on the rod accommodated by said passage, said head having a plurality of segments with vertical slots therebetween corresponding to the form of the cross to permit the segments 115 on the head to project above the cross when the head is raised. 120

5. In a double seaming machine, the combination of a framework, a lifting rod and a head carried by the rod and divided by in- 125

- tersecting vertical slots into radial segments, a slotway in each segment, a can holder pivoted in each slotway, and a spring controlling each holder.
5. 6. In combination, a frame work, a shaft mounted therein, a series of large cams upon said shaft, an upper intermediately pivoted lever actuated from each cam, a sleeve operated by each said lever having oppositely inclined cam surfaces, a seaming disk below each sleeve, intermediately pivoted levers carried by each disk, rollers carried by said levers and engaging with the adjacent cam surfaces, a chuck carried by said seaming 10 disk having a milled circumferential flange, seaming rollers controlled by said intermediately pivoted levers, a series of small cams attached to the aforesaid large cams, a series of clutches controlling said small 15 cams, a series of lifting rods actuated by said small cams, and a can supporting head on each rod, substantially as described.
15. 7. In a can seaming machine, the combination with a rotatable support and means for seaming cans carried by said support; of a foot carried by said support for reforming a distorted previously formed flange of a can in advance of the seaming means.
20. 8. In a can seaming machine, the combination of a rotary support, seaming means thereon, and a foot on said support for reforming or correctly shaping a previously formed flange to be seamed prior to seaming same and for preventing distortion thereof during double seaming.
25. 9. In a double seaming machine, the combination of a support, seaming rollers thereon, means for presenting a can to said rollers; means for controlling such presenting means; a foot attached to said support adjacent the seaming rollers for reforming or correctly shaping the previously formed flanges that are to be seamed just prior to seaming; means for engaging the seaming rollers with the cans to be seamed, and means for discharging the seamed can.
10. In a double seaming machine, the combination of a seaming disk, means for controlling the rotation of such disk, seaming rollers slidably attached to such disk, means for presenting a can to said rollers; means for controlling such presenting means, and a foot on the disk for re-forming or correctly shaping the previously formed flanges prior to seaming them; means for engaging the seaming rollers with the cans to be seamed, means for controlling the said engaging means, and means for discharging the seamed can.
15. 11. In a double seaming machine, a shaft, a bevel wheel thereon, a clutch controlling such wheel, a hollow vertical spindle driven from such wheel, a disk attached to the spindle, and seaming rollers carried by such disk; with devices fixedly attached to such disk each having a foot adapted to reform the previously formed flanges prior to seaming them.
20. 12. In a double seaming machine, a shaft, a series of bevel wheels upon said shaft, a clutch controlling each bevel wheel, a hollow vertical spindle driven from each bevel wheel, a seaming disk attached to each spindle, seaming rollers carried by each disk, and opposite devices attached to each disk 25 and having feet adapted to reform previously formed end flanges.

In witness whereof, we affix our signatures in the presence of two witnesses.

JAMES JOSEPH GRIFFIN.
